(No Model.)

W. E. CRAM & J. H. L. CLEGG.
ELECTRIC GAS LIGHTING APPARATUS.

No. 599,121.

Patented Feb. 15, 1898.

UNITED STATES PATENT OFFICE.

WILLIAM E. CRAM AND JAMES H. L. CLEGG, OF BOSTON, MASSACHUSETTS;
SAID CLEGG ASSIGNOR TO SAID CRAM.

ELECTRIC GAS-LIGHTING APPARATUS.

SPECIFICATION forming part of Letters Patent No. 599,121, dated February 15, 1898.

Application filed April 30, 1897. Serial No. 634,583. (No model.)

To all whom it may concern:

Be it known that we, WILLIAM E. CRAM and JAMES H. L. CLEGG, of Boston, in the county of Suffolk and State of Massachusetts, 5 have invented certain new and useful Improvements in Electric Gas-Lighting Apparatus, of which the following is a specification.

This invention relates to electric gas-lighting apparatus, and has for its object to provide an appliance by means of which the gas will be automatically lighted by the act of turning on a gas-cock, and in case the flame should be extinguished while the gas is flowing the same will be automatically relighted. 15

The invention consists in the improvements which we will now proceed to describe and claim.

Of the accompanying drawings, forming 20 part of this specification, Figure 1 represents a side elevation of a gas-bracket constructed in accordance with our invention. Fig. 2 represents a top plan view thereof. Fig. 3 represents a side elevation of the burner, the 25 electromagnet-casing being shown in section. Fig. 4 represents a top plan view of the burner. Figs. 5 and 6 represent sections on the line 55 of Fig. 1, showing the devices for making and breaking the electric circuit by means of 30 the key. Fig. 7 represents a modified form of the circuit-breaker or switch.

The same letters of reference indicate the same parts in all the figures.

Referring to the drawings, *a* designates the 35 gas-burner, which is provided with the usual form of tip *a'*, and the lower part of which is composed of malleable iron, which constitutes a core for an electromagnet *b*. An armature *c* is let into recesses in a flange *b'* at the upper 40 per end of the magnet and a pole-piece *b²* at the lower end thereof, the said armature being pivoted at *c'* to the flange *b'* and being provided with a light spring *c²*, by means of which its lower end is normally kept at a slight 45 distance away from the inner end of the recess in the pole-piece *b²*. A cylindrical casing *d* incloses the magnet. The armature *c* is prolonged to form an arm above the casing, its end being arranged in proximity to the slit in the gas-tip *a'* and being preferably tipped with a platinum contact-point *c³*. 50

e designates an expansion-strip or thermostat, composed preferably of two metals, such as iron and copper, which have different coefficients of expansion and affixed to or formed on a collar *e'*, which surrounds and is insulated from the burner *a*. The said expansion-strip is connected with one of the wires *b³* from the electromagnet, the other wire *b⁴* being carried back along the bracket 60 and connected with a binding-post *f*. To the shank of said binding-post is affixed a flexible contact-strip *f'*, which is adapted to be moved into or out of contact with the projecting shank of a binding-post *g*, the two binding-posts being insulated from surrounding metal and mounted in a base *h*, which is attached to the gas-bracket. The gas-cock *i* is provided on its lower portion with a key *i'* and on its upper end with a chamfered or 70 cam-shaped head *i²*. The contact-strip *f'* is shod on its under side with a piece of insulating material *f²*, which rests against the cam-face of the head *i²*, and said strip is held by its tension out of contact with the post *g* when 75 the key *i'* is in a crosswise position and the gas turned off, Figs. 1, 2, and 5. When the gas is turned on by moving the key *i'* to the position shown in Fig. 6, the strip *f'* is brought into contact with the post *g* and the electric 80 circuit is completed at this point.

The expansion-strip *e*, which is preferably provided with a platinum contact-point, is normally in contact with the platinum point *c³* at the upper end of the armature *c* and is 85 adapted to stay in this position as long as it remains cold; but when heated, as by the gas-flame, said strip uncurls slightly and its end moves out of contact with the tip *c³*.

As is usual in electric gas-lighting devices 90 the gas-bracket itself acts as one of the electrical conductors and a battery and spark-coil are placed in the circuit, which latter may readily be traced in the drawings through the binding-post *g*, the contact-strip *f'*, the binding-post *f*, the wire *b⁴*, the electromagnet *b*, the expansion-strip *e*, the armature *c*, and the gas-bracket. 95

It will now be seen that when the key *i'* is moved to the position shown in Fig. 6 to admit gas to the burner the circuit will be completed and the magnet *b* energized. The 100

lower end of the armature *c* is then attracted and is immediately released by the breaking of the circuit between the end of the expansion-strip *e* and the contact-point *c*³, a spark being formed at this place. A rapid vibration of the armature ensues, and a succession of sparks is formed which ignites the stream of gas issuing from the tip of the burner. The heat of the gas-flame then immediately causes the expansion-strip *e* to separate from the end of the armature, as shown in Figs. 3 and 4, thereby breaking the electric circuit. If, at any time, the gas-flame should be extinguished while the cock *i* is in its open position and the switch *f*' *g* closed, as shown in Fig. 6, the said expansion-strip will return in a few seconds to its normal position of contact with the point *c*³, sparking will ensue, and the gas will be thereby automatically relighted.

In Fig. 7 we have represented a top plan view of a slightly-modified form of switch, whose operation will readily be understood without explanation.

From the above description it will be seen that we have provided a simple, easily-constructed, and easily-applied device for automatically lighting gas and for preventing accidents caused by inadvertently blowing out the flame.

We do not confine ourselves to the exact construction of any of the parts or features of the above-described device, since it is obvious that our invention is capable of various forms of embodiment not differing essentially from that set forth.

We claim—

1. In a device of the character specified, the combination with a gas burner and cock, 40 of a switch operated by the movement of said cock for making and breaking an electric circuit, an electromagnet arranged in said circuit and having a vibratile armature provided with a contact member arranged in 45 proximity to the orifice of the gas-burner, and a thermostat arranged in said circuit and

adapted to coact with the vibratile member in causing a series of gas-igniting sparks, and to be expanded by the heat of the gas-flame, so as to separate the sparking-points 50 to break the electric circuit at the point of sparking, and to keep them separated during the existence of a flame.

2. A device of the character specified, comprising a gas-burner, a cock for governing 55 the flow of gas thereto, means operated by the movement of said cock for making and breaking an electric circuit, a pivoted vibratile member actuated by a magnet and an expansion-strip attached to the burner below 60 the end of the same and curved around said burner so as to bring its free end into proximity with the vibratile member and with the opening in the burner, the said vibratile member and expansion-strip coöperating to 65 produce igniting-sparks, and the said expansion-strip being adapted to be acted on by a flame to separate the sparking-points to break the electric circuit at the point of sparking.

3. A device of the character specified, comprising a gas-burner, a cock for governing the flow of gas thereto, means operated by the movement of said cock for making and breaking an electric circuit, a thermostat included in said circuit, an electromagnet consisting of a core forming a part of the gas-conduit and a helix surrounding said core, the said magnet having a flange at its upper end and a pole-piece at its lower end, and an armature pivoted in a recess in the flange and 80 having its lower end let into a recess in the pole-piece, all arranged to operate substantially as described.

In testimony whereof we have signed our names to this specification, in the presence of 85 two subscribing witnesses, this 28th day of April, A. D. 1897.

WILLIAM E. CRAM.
JAMES H. L. CLEGG.
